UNITED STATES PATENT OFFICE.

FRANK RYNDZONAK, OF GLIDDEN, TEXAS.

WHEEL CLAMP.

Application filed May 16, 1922. Serial No. 561,432.

To all whom it may concern:

Be it known that I, FRANK RYNDZONAK, a citizen of the United States, residing at Glidden, in the county of Colorado and State of Texas, have invented new and useful Improvements in Wheel Clamps, of which the following is a specification.

This invention relates to clamps for attaching a wheel of a railway car or the like to the rail supporting such wheel and is especially adapted for use in holding the wheel stationary on the rail when the journal box is to be lifted for renewing brasses or for like operations.

Objects of the invention are, the production of a device which may be readily and quickly attached to the rail and wheel; which is simple in construction and operation and economical to manufacture; which will not interfere with the jack used for raising the journal box, and which may be disassembled for storage when not in use.

A further object is to produce a device of the character referred to which is adaptable to varying conditions.

In the drawing:

Fig. 1 is a perspective view showing the device in operative relation to a rail and wheel;

Fig. 2 is a side elevation of the same on a slightly larger scale than Fig. 1; and

Fig. 3 is a section on line 3—3, Fig. 2, showing the relation of the parts.

Referring to the drawings in detail, 10 designates an ordinary track rail, 11 the wheel of a car or the like running on said rail, and 12 the rim of said wheel.

In jacking up the journal boxes of a car wheel for inserting brasses or for any other purpose the car wheel should be locked against movement on the rail. For this purpose I have provided the device forming the subject-matter of my invention, which comprises an arm 13 adapted to rest upon the head of a rail and to project laterally therefrom. This arm is preferably rectangular in cross-section and is provided at one end with a jaw 14 which extends at substantially right angles to the arm and is adapted to hang down over and grip one side of the head of the rail. A second jaw 16, which is adapted to grip the opposite side of the head of the rail, is carried by an eye which corresponds in shape to the cross-section of the arm 13. The arm 13 extends through said eye and the jaw 16 is thus slidably

mounted on the arm 13. The jaws 14 and 16 are provided at their lower ends with horizontally extending portions 15 and 17, respectively, which are adapted to grip the under-sides of the head of the rail. These portions 15 and 17 are preferably provided with roughened or toothed surfaces 18 and 19 to adapt them to better grip the surface with which they contact. Any relative angular movement between the jaws 14 and 16 will cause the eye of the jaw 16 to bind on the arm 13 and thus secure the jaw 16 against movement longitudinally of the arm 13.

Slidably mounted on the arm 13 in a manner similar to jaw 16 is a bracket arm 20 which, when the device is attached to a rail, extends in parallelism with the rail, the sliding connection between the arm 20 and the arm 13 being preferably in the form of an eye 21 at or adjacent to one end of said bracket arm, through which eye the arm 13 is adapted to slide. The arm 20 curves downwardly from the eye 20 and then extends substantially in a horizontal plane. This construction of the bracket arm gives it a certain resiliency for a purpose which will hereinafter appear. The end of the arm 20 opposite the eye 21 is bent vertically upward to form a stem 22, as shown in Figs. 1 and 2, and mounted on this upwardly extending portion is a clamp member 23 which is vertically adjustable on the vertical stem 22 and is held against accidental slipping thereon by the roughened surfaces 24 on opposite sides of said stem. The clamp 23 has a projecting nose 26 which is adapted to extend laterally from the member 22 and to grip the rim 12 of a wheel and hold it locked to the rail.

On the end of the arm 13 I provide a turn-button 25, which when in certain positions, namely, vertical and horizontal, will prevent the eye 21 of the arm 20 from slipping off of the arm 13, and when in other positions at 45° to the horizontal, will permit the removal of the said arm 20. By this construction the device may be disassembled for storage, or the arm 20 may be reversed in its position on the arm 13 and caused to extend in the opposite direction from that shown in the drawing.

In applying the device to a rail and wheel, the jaw 14 is hooked over one side of the head of the rail with the hook portion 15 under said head of the rail and the jaw 16 is

brought to a position with the projection 17 extending under the head of the rail on the other side thereof. The arm 20 is then adjusted upon the arm 13 so as to properly position the clamp 23 relative to the wheel to be locked. The clamp is then brought down into contact with the flange of the wheel and a crow-bar may be slipped under the arm 20 and the arm raised slightly, therefore allowing the clamp 23 to slide further down on the member 22. When the crow-bar is removed, the resiliency of the arm 20 will draw the clamp 23 firmly against the wheel, preventing its movement along the rail.

Any movement of the wheel 11 on the rail 10 will, through the engagement of the clamp 23 with the flange of said wheel, tend to rock the arm 20 and with the latter rotate the arm 13 by reason of the engagement of the eye 21 of the arm 20 with the arm 13. But such rotation of the arm 13 will be resisted by the engagement of the jaws 14 and 16 with the head of the rail and the slight resulting relative angular movement between the jaws 14 and 16 will cause the jaw 16 to bind on the arm 13, thus securing the jaw 16 against movement longitudinally of the arm 13.

30 What is claimed as new is:

1. A device for clamping a car wheel to a rail, comprising a pair of jaws for attaching the device to a rail, a resilient bracket arm, and a vertically adjustable clamp on said bracket arm adapted to be brought into position against the flange of the wheel.
2. A device of the character described, comprising an arm having a jaw attached to the end thereof, a jaw slideable on said arm and secured by angular movement relatively to said first-named jaw against movement longitudinally of said arm, said second-named jaw cooperating with the first named

jaw to clamp the device to a rail, a bracket arm adjustable on said first named arm, and a vertically adjustable clamp on said bracket arm. 45

3. In a device of the character described, an arm having a jaw on the end thereof and an adjustable jaw cooperating therewith to secure the arm to a rail, a resilient bracket arm extending from said first named arm and adapted to lie in parallelism with the rail, and a vertically adjustable clamp secured to said bracket arm. 50 55

4. A device of the class described, comprising an arm adapted to be secured to a rail and to extend laterally therefrom when so secured, a bracket arm adjustable on said first named arm having a vertically extending portion, and a clamp adjustably secured to said vertical portion, as and for the purpose described. 60

5. A device for securing a car wheel to a rail, comprising an arm adapted to be secured to the rail, a bracket arm adjustable on said first named arm, a turn-button on the end of the first named arm which, when in one position, prevents removal of the bracket arm from the first named arm and which may be turned to a position to permit removal of said bracket arm, and a clamp on said bracket arm. 65 70

6. A device for securing a car wheel to a rail, comprising an arm adapted to be secured to the rail, a bracket arm adjustable and reversible on said first named arm, and a clamp on said bracket arm. 75

In testimony whereof I have hereunto set my hand in presence of two subscribing witnesses. 80
